UNITED STATES PATENT OFFICE.

ALEXANDER P. BROWNE, OF BOSTON, MASSACHUSETTS.

PORTABLE BATHING-TUB.

SPECIFICATION forming part of Letters Patent No. 268,862, dated December 12, 1882.

Application filed October 25, 1880. (No model.)

To all whom it may concern:

Be it known that I, ALEXANDER P. BROWNE, a citizen of the United States, residing at Boston, in the county of Suffolk and State of Massachusetts, have invented certain new and useful Improvements in Portable Bathing-Tubs, of which the following is a specification.

My invention relates to portable pans or tubs for bathing purposes, and has for its object greater convenience and greater economy of water in their use than have hitherto been attained.

In the manufacture of vessels of this class, which are by their nature in use but a small portion of the time, it has hitherto been found convenient and desirable to construct them of a shallowness sufficient to enable them, when not in use, to be slid under a bed or couch in the sleeping apartment, whereby they are readily removed from view. But this construction has been found defective, in that it necessitates having the interior of the pan or tub of such an area and conformation that an unduly large amount of water is required to be transported to and used in the tub to give a sufficient depth of water for bathing purposes. Again, this construction, distributing the body of water over so large an area, renders difficult and inconvenient the emptying of the tub or pan after bathing, and this difficulty is enhanced by the fact that the sole means of emptying heretofore provided has been two handles arranged at opposite sides upon the rim, by which construction the leverage of the water in the pan is exerted unfavorably against the strength of the person lifting the tub to empty it, and tends to cause the spilling of the water upon the carpet or floor. These defects before mentioned are remedied by the improvements herein described, and shown in the accompanying drawings, in which—

Figure 1 is a view in perspective, and Figs. 2 and 3 views in section, showing the improvements described. Figs. 4 and 5 are views in detail of the emptying-support.

In a bathing-pan of ordinary construction a sheet, strip, or wall of tin or other suitable material, A, is inserted to form within the pan a water-tight inclosure, B, into which the clean

water is to be poured. The rest of the interior of the pan forms a second inclosure, C, in which the bather stands. This last inclosure is provided with an outlet, D, to facilitate the emptying from C of the water which falls into it during the operation of bathing simultaneously with that remaining in B. The bottom of the inclosure B being of considerably less area than the entire bottom of the tub or pan, less water will be needed to fill it to a depth sufficient for bathing purposes than would be required to cover the whole bottom of the tub to the same depth, and thus less water is required to be transported to the tub and used therein. At the same time the tub or pan may still be constructed throughout of sufficient shallowness to be readily put away under a bed or similar article of furniture during the day-time or when not in use.

E is a support or bail attached to a tub or other vessel for containing fluid in such a manner that it may, when desired, be thrown forward with its ends resting upon the floor. It is so constructed that when the tub or other vessel is to be emptied the feet of the support form a fulcrum upon which the tub may be raised until tilted sufficiently to allow its contents to flow out into any suitable receptacle. When not in use the support may be folded back and thus put out of the way. By the use of such a fulcrum or support the labor of emptying a tub or other vessel is, as will readily be seen, greatly diminished.

I claim—

1. A portable bath tub or pan having two compartments separated by a permanent partition to form a receptacle for water and another for the bather, substantially as described.

2. A portable bath tub or pan having separate compartments, one for water, the other for the bather, provided with suitable outlets for discharging their contents, substantially as described.

3. A hinged emptying-support attached to and in combination with a liquid-containing vessel, substantially as shown.

ALEX. P. BROWNE.
